[57] ABSTRACT

An audiovisual record having a spiral information track and an image-disc rotationally secured thereon.

An audiovisual record comprising a support plate, an image-disc rotationally secured thereon and a sound-disc rotationally secured thereon.

An audiovisual apparatus accepting for reproduction the above-referred audiovisual records.

AUDIOVISUAL SYSTEM

FIELD OF INVENTION

This invention relates to audiovisual records and to apparatuses accepting for reproduction these audiovisual records.

DESCRIPTION OF THE PRIOR ART

Slide projectors, that is projectors accepting for projection still image transparencies of "slides," have been widely accepted as an entertainment, educational, advertising and, in general, information-storing and reproduction medium. It has been also widely accepted that the addition of "synchronized" sound greatly increases the usefulness and value of projectors of all kinds, whether they are of the "movie" or "still" variety.

The addition of synchronized sound to still images, or slides, always posed considerable technical difficulties and originally the sound was contained in a totally separate medium, such as a separate phonographic record or magnetic tape. It is evident that as long as two separate media were employed, "synchronization", in the accepted sense of the word, was impossible.

Several years ago, the inventor of the present invention solved the synchronization problem by associating a generous amount of audio information with each and every slide. In fact, according to the teachings of his U.S. Pats. Nos. 3,122,053, 3,122,054, 3,282,154, 3,302,520, 3,480,356, 3,644,032, 3,717,407, 3,730,618, etc. each and every one of his audiovisual tablets, of special construction and attributes, contains a stationary sound track, spirally disposed about a stationary, projectable, image.

In some cases however, it was found that this was not entirely satisfactory, and one single image and its associated sound was not sufficient, but instead, a series or sequence of projectable images with their accompanying sound was necessary. Accordingly, in his U.S. patent applications Ser. Nos. 500,753 and 500,754, the inventor of the instant invention taught the principles of an audiovisual disc incorporating a series of projectable images, disposed on an annular ring surrounding a spiral sound track, which also included special pulses for the step-like rotation of the disc, at the predetermined, desired, time intervals, in order to expose to the optical projection beam of a specially designed and constructed audiovisual reproduction apparatus, the individual images of the disc.

The arrangement of projectable images around a spiral track was dictated by technical considerations, such as the best use of the available space on the disc, consistent with the best disposition of the optical and audio components on the special audiovisual reproduction apparatus. It was later discovered that while the placing of the images around the sound track allowed a substantial area for each and every image (which, in turn, resulted in good, clear and sharp projections), it increased considerably the manufacturing cost of the audiovisual discs, since it was either necessary to have all images printed on a fairly large, and therefore expensive, photographic film, or alternatively, each image, or group of images, had to be individually mounted on the special audiovisual disc, again a time-consuming and expensive operation.

Therefore, in his Patent Application No. 304,202, the inventor of the present invention taught a special

apparatus capable of audiovisually reproducing an audiovisual disc having a series of images disposed within an annular region surrounded by a spiral sound track. This permitted a more economical mass-reproduction of audiovisual records in some specific cases. In these two alternatives, i.e. images surrounding or surrounded by the sound track, both images and sound track are carried on a single audiovisual medium and this makes possible the economical mass-reproduction of the special records. There is one specific problem which may, or may not, be of great importance, namely that during the step-wise rotation of the audiovisual disc (in order to expose another image to the projection beam) the sound must be interrupted.

OBJECTS OF THE INVENTION

It is therefore the object of the present invention to provide special audiovisual records incorporating a series of projectable images and their accompanying sound, which records are capable of uninterrupted sound reproduction, even during the stepwise change of image.

It is a further object to provide such an audiovisual record having a series of visually reproducible images and their associated sound arranged in a manner that makes possible an easy and economical manufacturing of these records.

It is a still further object of the present invention to provide such audiovisual records, each comprising a sound record having a spiral sound track and an image-disc rotationally secured to the sound record about a point distinct and at a distance away from the center of the spiral track.

It is a still further object of the instant invention to provide audiovisual records, each comprising a support on which two separate discs, one sound disc and one image-disc, are rotationally mounted on separate centers, distinct and at a distance away from one another.

It is a still further object of the invention to provide audiovisual apparatuses of special design, construction and attributes, which readily accepts for audiovisual reproduction the special, novel, audiovisual records of the invention.

It is a still further object of the present invention to provide such novel apparatuses characteristic in that they have two distinct spindles, one sound-spindle and one image-spindle, thus enabling them to achieve a positive and efficient positioning of the two main components of the novel audiovisual records of the invention, namely the image-disc and the sound-record.

It is a still further object of the present invention to provide such novel apparatuses having novel arrangements of electromechanical components and parts which make possible an excellent sound reproduction from relatively simple and inexpensive records.

It is a still further object of the present invention to provide such novel apparatuses with novel arrangements of sound scanning components which make possible an excellent sound reproduction even from very thin and flexible sound records.

It is a still further object of the present invention to provide novel audiovisual apparatuses of simple construction, having their components arranged in a manner that makes possible massmanufacturing at greatly reduced costs.

Other objects of the invention will become evident from the ensuing description, illustrations and claims.

BRIEF DESCRIPTION OF THE FIGURES

FIG. 1 is a plan view of one preferred embodiment of an audiovisual record according to the invention.

FIG. 2 is a vertical, sectional view of a simplified version of an embodiment of an apparatus according to the invention, with some parts removed to facilitate the description. FIG. 3 is a plan view of another preferred embodiment of an audiovisual record according to the invention.

FIG. 4 is a vertical, sectional view taken along line 4-4 of FIG. 3.

FIG. 5 is a view, similar to FIG. 2, of another simplified embodiment of another apparatus according to the invention particularly suited to accept audiovisual records according to the invention, such as those shown in FIGS. 3 and 4.

DESCRIPTION OF PREFERRED EMBODIMENTS

The invention will now be described in some detail in connection with specific embodiments of both the novel audiovisual information devices and the novel apparatuses accepting for audiovisual reproduction these novel audiovisual devices. The ensuing descriptions will be based on simple forms of such devices and apparatuses, but other, different, or more complex versions and modifications are evidently possible within the spirit of the invention.

FIGS. 1, 3 and 4 illustrate two embodiments of novel audiovisual information devices according to the invention. Referring to FIG. 1 it can be seen that it consists of essentially two parts, rotationally connected to one another. Thus, numeral 10 designates a substantially flat (and optionally thin) sheet or plate having a spiral sound track 12. Substantially at the center of the spiral, sheet 10 may, optionally, be formed with an aperture, or hole, or perforation 16. The sound track itself may be of any convenient type, for example, phonographic, magnetic, optical, electrostatic, etc. The actual shape of sheet 10 may be rectangular as illustrated in FIG. 1, disc-shaped as illustrated in FIG. 3, or may be of any convenient or desired shape and form, as dictated by design, marketing and manufacturing considerations.

Image-disc 11 is rotationally mounted on sheet 10 for example by means of simple bearing means 15. Such bearing means are again a matter of design choice and in one of their simplest forms may consist of an eyelet. Disc 11 carries a series of images 14, disposed in an annular region, substantially concentric to bearing 15, in other words all such images are substantially equidistant from the center of bearing 15. Disc 11 may also be formed with, or carry, one or more indentation, perforation, or the like, employable in the reproduction apparatus for the step-wise rotation of the disc in order to expose successive images to a projection beam. For example, a series of holes 17, all equidistant from the central axis of bearing 15 may conveniently exist on disc 11 for this purpose. The location of these holes, indentations, or perforations, may be anywhere on disc 11 and not necessarily as shown in the FIGS. 1 and 3, that is, they may be inside or outside the annular area of images 14, including the very edge of the disc, in which case they may take the form of notches. And again, just one (or two or more) notch(es), hole(s), perforation(s), indentation(s), or combinations of them, may be sufficient. In this case, the reproduction apparatus may conveniently have a rotating link, or wheel, carry-

ing for example, a pin, which may engage such hole(s), notch(es), perforation(s) indentation(s), or the like, in order to impart to the disc 11 the required step-like rotation.

FIGS. 3 and 4 illustrate another embodiment of an audiovisual information device according to the invention, substantially similar to the above described except that the sheet 10 is discshaped, essentially in the usual phonographic fashion, and that both sheet 10 and disc 11 are bearingly supported on support member 21 and may thus freely and independently rotate about their respective bearings 15 and 16. These bearings 15 and 16 may again be as complex or simple as desired, and may be optionally be simple eyelets. Sheet 10 and disc 11 may be in all respects similar to their equivalent members described in connection with FIG. 1 that is, sheet 10 carries the sound track and disc 11 the images 14 and optionally, one or more notches, indentations, perforations, etc. for example a series of holes 17, located as shown or as more generally described in connection with FIG. 1.

The support member 21 may be of any convenient type, shape, form or size and may be equal, smaller or larger than the combined sizes of members 10 and 11, but, for illustrative purposes, it is shown in FIG. 3 and 4 as being fairly small and rectangular in shape. Furthermore, and simply as a matter of design choice, it is shown as being thicker on the side facing the sheet 10, the extra thickness being an integral part of support 21, or being provided during the manufacturing or molding process, for example by spacer 23. It now becomes evident that this support number 21 permits both sheet 10 and disc 11 to freely and independently rotate about their respective centers. Furthermore, the center of rotation of disc 11 may be actually located under or over the area facing, or opposite to, the spiral sound track 12, thus, making possible a more compact audiovisual device. But, in the final analysis, the eyelet 16 may be firmly crimped and/or sheet 10 may be laminated, cemented or otherwise bonded to support 21, in which case, only disc 11 is freely rotating and in this case, the embodiment illustrated in FIGS. 3 and 4 becomes simply another alternative arrangement of the device illustrated in FIG. 1, with the optional exception that it allows a more compact device by optionally again placing the bearing within, or under, the sound spiral. Of course, when support 21 and sheet 10 are bonded together, as above described, and thus (or otherwise) form one single piece, the eyelet 16 becomes entirely optional and may be substituted by the usual phonographic hole or any other type of hole or locating indentation or perforation. In the final analysis, the existence of such hole, indentation, eyelet, etc. is entirely optional.

The above described audiovisual information device may be conveniently employed with the special apparatus, of novel construction and attributes to be presently described. Thus, FIG. 2 illustrates in a somewhat schematic and over-simplified manner, the vertical cross-section of an embodiment of an apparatus according to the invention, particularly suited for the audiovisual reproduction of devices as those previously described in connection with FIGS. 1, 2 and 3. Numeral 20 generally designates the frame and/or housing of the apparatus. The sheet 10 of the audiovisual device is supported by plate-member 26, formed with a large opening or window exposing the sound track 12, for scanning by

transducer 42. Facing the sound track 12 is turntable 30 which rotates about shaft or spindle 31, in the usual phonographic fashion. Spindle 31 is fixedly secured to the frame or housing of the apparatus, for example by means of flange 32. As a further support to the center of the sheet 10, spindle 31 may conveniently carry flange 33. The spindle 31 may also protrude over the flange 33 and thus pass through hole 16 of sheet 10 to properly locate the spiral sound track in relation to the rotating transducer. If hole 16 is large, (such as that currently employed in the 45 rpm phonographic records) or if such hole 16 is of other than circular shape, then it might be more convenient to engage such a hole with an appropriately shaped extension, or hub, of flange 33. It must be evident that the spiral sound track remains stationary and the transducer rotates. Therefore, transducer 42 is mounted on arm 38, which is pivotally attached to turntable 30 in the usual phonographic manner, i.e. about two mutually perpendicular axis, allowing the arm the usual two degrees of freedom. Alternatively the arm may be of the radical, pantographic, or any of the several other types well-known in the art. Similarly, the transducer may be of the phonographic, magnetic etc. type depending on the type of sound track employed but, in all cases, the "working-end" of such transducer, such as the stylus 44, is in sound-reproducing relation with the sound track 12, in order to follow this spiral track and reproduce the information contained therein. It is convenient, although not entirely necessary, to provide another shaft or spindle 35 to engage the central hole of bearing 15 of disc 11, in order to provide a stable and dependable locating and rotational support to this image-carrying disc 11.

In order to optically scan the image 14 of the disc 11, an appropriate assembly must be provided, for example, the optical assembly illustrated in FIG. 2, comprising projection lamp 50, condensing lenses 52 and projection cell 56, all supported by appropriate supports such as brackets 53, 54, and 58. In this arrangement, the condensing lens assembly 52 directs the light emitted by lamp 50 onto image 14, while projection cell 56 focuses the imaging rays emerging from image 14 onto a projection screen, which may be housed within the apparatus (for example, a "rear screen") or may be placed elsewhere. The above described arrangement of optical components must be considered as an example of the several variations and types possible and was only used for descriptive purposes. For example, a prism or mirror may be placed after the projection lens 56 to bend the imaging rays and direct them in the desired path and onto a projection screen. It is also evident that the illuminating source and condensing lens system may be over the disc 11 and the projection lens cell 56 under it, all this according to well known in the art principles and within the spirit of the invention, the actual number, disposition and arrangement of components being a matter of design choice.

Since the transducer rotates and the sound track is stationary, it is necessary to conduct the electric signals generated by the transducer to the electronic equipment and for this purpose, a slip-ring arrangement 61 and brushes 62 may be conveniently provided, in the well known manner.

An appropriate mechanism must be provided to impart the necessary rotational movement to turntable 30, (or generally, to the rotating, transducer-carrying

member) and this may be accomplished in several ways known in the art, such as motors and belts, wheels, gears, etc., for example, as illustrated in FIG. 2, by means of electric motor 73, and rubber-rimmed wheel 71 (mounted on the motor shaft or, still better, arranged as an "idler-wheel", in the well known manner) contacting and imparting rotational motion to turntable 30.

It is necessary to selectively rotate the disc 11 in a step-wise fashion in order to expose successive images 14 to the projection beam and, for this purpose, any of the well known means may be conveniently employed, for example reciprocating links, toothed gears, etc., the final selection being again a matter of design choice but, as an example, a simple arrangement will be described, this arrangement not being necessarily the best but being convenient for descriptive purposes: a toothed wheel 77 inclined at an angle with respect to the plane of disc 11, may engage the perforations of the disc 11. Toothed wheel 77 may be coaxially secured and turn with gear 74, which meshes with pinion gear 75 carried on the shaft of small motor 76, mounted on bracket 78, secured directly or indirectly, on the frame or housing of the apparatus.

Activation of motor 76 may be conveniently triggered by means of command information or pulses contained in the sound track, this sound track being of the monoral, two-channel or any other type, and when more than one channel is provided, one channel may conveniently carry the command information and the other channel(s) the sound information.

An audiovisual information device such as that illustrated in FIGS. 3 and 4 and above-described in some detail, may also be conveniently placed for audiovisual reproduction in the above-described apparatus. Whether the disc 10 of FIG. 3 rotates about bearing 16 or not is of no importance, since the disc 10 will be held immovable in the apparatus of FIG. 2 and the information-scanning transducer will rotate and scan the information contained in the spiral information track. But it is also possible to provide another type of novel apparatus, such as that illustrated in FIG. 6, in which the support 21 is held immovable on apparatus support plate 26 by means of spindles 31 and 35 and/or otherwise and a rotational movement is imparted to disc 10 by means of an appropriate arrangement, such as a turntable or two opposed rollers 85 and 86 which contact and engage from opposite sides the disc 10. In this manner, the disc 10 is "pinched" between these two rollers, at least one of which is rotationally driven by well known means, not shown. Since the disc 10 rotates, the transducer does not have to also rotate but may be carried on an appropriate arm, in the conventional and well known phonographic manner. In other respects the apparatus of FIG. 5 may be substantially similar to that illustrated in FIG. 2 and therefore same numerals designate similar parts and components.

If the disc 10 is thin and flexible, it might be better to substitute the conventional phonographic arm with the "pincers-like" arm conceived by the inventor of the present invention and described in some detail in his U.S. Pat. No. 3,408,080. Essentially, this pincers-like arm 81 has a substantially U-form shape and carries a transducer 80 on one leg or tip, a small pad 83 on the other, the working end 82 of the transducer (for example the "stylus") facing the small pad. The pad and the transducer are forced against one another by spring

means not shown and thus the disc 10 is "pinched," in a pincers-like fashion, between the transducer and the pad. This "pincers-like" arrangement permits exceptionally good contact between the working end of a transducer and the sound track and therefore makes possible excellent information-scanning efficiency which, in turn, results in excellent sound and information reproduction even from thin, flexible, and even slightly bent records.

The invention has been described by reference to a few specific embodiments thereof, however, it will be understood that the principles of the invention can be carried out by variations, modifications and combinations of the above-described embodiments of the invention and therefore it is not intended to exclude such variations, modifications and combinations which properly fall within the spirit of the invention.

Thus, images 14 may not necessarily be of the photographic or diapositive type but may generally be of any visually-reproducible imaging-information type. By this it is meant that the images may not be readily recognizable by the naked eye but may be of a type which may be converted into a recognizable image by appropriate electronic, optical, electro-optical, etc. devices, which may be optionally, incorporated in the apparatus of the invention.

The term "sound track" was often used in the above descriptions and this term will also include pulses and any other desirable form of information. Therefore wherever the term sound track is employed, it will be understood that the more general term "informations track" may be substituted. This information track may be of any desirable type such as phonographic, magnetic, electrostatic, etc. and the scanning transducer of the apparatus will be of an appropriate type specifically suited to the particular type of information track employed.

In the description of the apparatus of FIG. 2 it was mentioned that the transducer 42 was mounted on an arm 38, pivotally secured to turntable 30, but as a matter of fact, a turntable is not an essential element, the only requirement being that the transducer 42 rotates about the axis of the spiral track and any means which accomplishes this is equally acceptable. For example, the arm 38 may be supported on a simple link rotating about a shaft whose axis substantially coincides with the axis of the information track.

When describing the novel apparatus and devices of the invention, emphasis was placed in the important and/or novel features and therefore, both in the description and the illustrations, parts well known in the art were omitted. For example, wires and cables providing electric current to motors and lamps and/or interconnecting electrical components were omitted. For the same reasons, the electronic and amplification components were not mentioned or illustrated, nor were specific housings and frames, but, it is evident that electronic components, mechanical frames and appropriate housings may be employed, as desired and as required.

In the information devices illustrated on FIGS. 3 and 4 and particularly in the embodiment in which the disc 10 rotates about bearing means 16, it is evident that the spiral information track 12 could also be placed on the surface of the sound disc 10 facing the image disc 11.

What is claimed is :

1. An audiovisual information device comprising at least two distinct recording media, including one sound-record and one image-disc, said sound-record having a spiral sound track thereon and said image-disc having a series of projectable images disposed substantially within an annular region substantially coaxial to the center of said image-disc, means mounting said image disc on said sound-record for rotational movement about said center of said image disc, said center of said image-disc and the center of said spiral being radially spaced-apart a distance which causes said image-disc and said spiral track to overlap.
2. An audiovisual information device according to claim 1, wherein said spiral sound track is disposed on a disc-shaped member which is also rotationally supported on said record for rotation about said center of said spiral.
3. An audiovisual information device according to claim 1, including second means on said image-disc, employable by the reproduction apparatus in which said device is used, for the step-wise rotation of said image-disc.
4. An audiovisual information device according to claim 3, wherein said second means include a series of perforations.
5. An audiovisual information device according to claim 3, wherein said second means include at least one perforation.
6. An audiovisual information device according to claim 1, wherein said sound record has a hole substantially coinciding with said center of said spiral.
7. An audiovisual information device according to claim 2, wherein said member has a hole substantially coinciding with said center of said spiral.
8. An audiovisual information device according to claim 1, wherein said sound record is substantially rectangular-shaped.
9. An audiovisual information device according to claim 1, wherein said sound track contains command information, employable in the reproduction apparatus in which said device is used for triggering a step-wise rotation of said image-disc, in order to expose successive images thereof to a projection beam in said apparatus.
10. An audiovisual information device according to claim 9, wherein said command information is command pulses.
11. An audiovisual information device according to claim 9, wherein said sound track includes more than one channel.
12. An audiovisual information device including two separate disc-shaped recording media, namely one sound-disc and one image-disc, said sound disc having a spiral sound track disposed substantially coaxially to the center of said sound-disc and said image-disc having a series of projectable images disposed substantially within an annular region coaxial to the center of said image-disc, a support member, means mounting both said image-disc and said sound-disc for rotation on said support member, said rotation being about their respective centers, which are radially spaced-apart a distance which causes said image-disc and said spiral track to overlap.
13. An audiovisual apparatus accepting for audiovisual reproduction an audiovisual information device comprising one sound record having a spiral sound track and, at a distance radially away from the center

of said spiral, bearingly supporting for rotation thereon, an image-disc having a series of projectable images disposed within an annular region coaxial to its center of rotation; said apparatus including:

- a. a rotating transducer which engages and follows said track in a sound-scanning relationship;
- b. optical projection means directed onto at least one of said images to optically scan and retrieve therefrom the imaging information contained therein;
- c. spindle means, whose axis is at a distance away from the center of rotation of said transducer, engaging said image-disc at its said center of rotation;
- d. record-supporting means supporting said sound record but leaving said track exposed to said rotating transducer.

14. Apparatus according to claim 13, including a second spindle means engaging an aperture located concentrically to said center of said spiral on said sound record.

15. Apparatus according to claim 13, including moving means, engageable with said image-disc, for its step-wise rotation in order to expose successive images to said projection means.

16. Apparatus according to claim 14, wherein said second spindle means also bearingly support said rotating transducer.

17. Apparatus according to claim 14, wherein said second spindle means is coaxial to the axis of rotation of said transducer.

18. Apparatus according to claim 13, wherein said transducer is first mounted on an arm, in substantially the phonographic fashion, and said arm is in turn mounted on a rotating member.

19. Apparatus according to claim 18, wherein said rotating member is a turntable.

20. Apparatus according to claim 13, wherein a projection lens system is focused on at least one of said images to project it onto a projection screen.

21. Apparatus according to claim 20, wherein said projection screen is included in said apparatus.

22. Apparatus according to claim 13, including a housing containing said apparatus.

23. An audiovisual apparatus accepting for audiovisual reproduction an audiovisual information device comprising a support member rotationally supporting thereon, on radially spaced-apart centers of rotation, one sound-disc having a spiral sound track coaxially disposed about its centers of rotation and one image-disc having a series of images disposed substantially within an annular region coaxial to the center of rotation of said image-disc; said apparatus including:

- a. support means immovably supporting said support member;
- b. spindle means coaxial to said center of rotation of said sound disc;
- c. second spindle means coaxial to said center of rotation of said image-disc;
- d. an optical beam directed onto at least one of said images to optically scan the imaging information contained therein;
- e. driving means for rotating said sound disc;
- f. a transducer engaging said sound track in an information-scanning relationship.

24. Apparatus according to claim 23, wherein said driving means include a pair of opposed rollers pressing between them said sound-disc, at least one of said rollers being rotationally driven.

25. Apparatus according to claim 23, including moving means, engageable with said image disc for its step-wise rotation in order to expose successive images to said beam.

26. Apparatus according to claim 23, wherein said transducer is mounted on an arm in substantially the phonographic fashion.

27. Apparatus according to claim 23, wherein said transducer is mounted on one of the two legs of a U-shaped arm, carrying a pad on its other leg, said pad and said transducer facing one another and pressing between them said sound-disc in a pincers-like fashion.

28. Apparatus according to claim 23, wherein a projection lens is focused on at least one of said images.

29. Apparatus according to claim 23, including a housing containing said apparatus.
